UNITED STATES PATENT OFFICE.

SMITH VROMAN, OF SAN FRANCISCO, CALIFORNIA, ASSIGNOR TO SAMUEL ALLEN
GUIBERSON, JR., OF SAN FRANCISCO, CALIFORNIA.

WELL-CASING SPEAR.

1,091,100.

Specification of Letters Patent. Patented Mar. 24, 1914.

Application filed October 4, 1913. Serial No. 793,366.

To all whom it may concern:

Be it known that I, SMITH VROMAN, a citizen of the United States, residing in the city and county of San Francisco and State of California, have invented certain new and useful Improvements in Well-Casing Spears, of which the following is a specification.

My invention relates to that class of well-casing spears in which an annular series of gripper-slips are fitted to tapered seats on a stock, whereby in running down in the casing said series of slips contract in circumference sufficiently to pass down freely, but expand in circumference on the lifting movement, so that the slips grip the casing.

The object of my invention is to provide a simple and effective spear of this class, and to this end my invention consists in the novel well-casing spear which I shall hereinafter fully describe by reference to the accompanying drawings, in which—

Figure 1 is an elevation of my well-casing spear. Fig. 2 is a vertical section, enlarged, the lower portion being broken away. Fig. 3 is a vertical section enlarged, the upper portion being broken away. Fig. 4 is a cross section on Y—Y of Fig. 1. Fig. 5 is a cross section on Z—Z of Fig. 1. Fig. 6 is a rear elevation of one of the gripper-slips. Fig. 7 is a cross section on X—X of Fig. 1.

1 is a stock with a central bore 2 opening upward from its foot nearly to its head. In the bore of the stock is slidably fitted the mandrel 3. The stock is formed in its body portion 4 with tapered gripper-slip-seats 5, the taper of which is upward, that is, said seats deepen from bottom to top. There may be any number of these seats symmetrically disposed about the circumference of the body portion, though, in practice, I have found three to be best, in that this number gives uniform gripping effect upon the casing consistent with strength in the stock. To each of the seats 5 is fitted a gripper-slip 6, the connection being best a dovetail one as indicated by the groove 7 in the seat, and the tongue 8 on the back of the slip. The relation of seats and slips is such that when the slips rise on their seats to their upper limits they lie flush with and continue the circumference of the body portion of the stock, but when and as they move downward they project beyond said circumference, after the manner of slips of this nature in

this type of casing-spears. The slips 6 are what may be termed free slips, in that they move freely on their seats, and their outer faces are suitably formed for gripping, as, for example, by the teeth 9.

About the upper portion of the stock is fitted slidably the loose head ring 10 which is formed on its upper face with an annular recess 11. A cross-key 12 lies in the recess 11 and said key traverses and is freely 60 65 70 75 80 85 90 95 100 105 110 115 120 125 130 135 140 145 150 155 160 165 170 175 180 185 190 195 200 205 210 215 220 bring the notch 24 of said mandrel opposite the end of the trigger-pin 22. The socket plug 25 of the trigger and trip device having first been removed to expose the head of the 5 trigger-pin 22, said pin is pushed in to cause its end to lie in the mandrel notch 24, and it is there temporarily held by the operator against the force of its spring 23, until the setting tool 20 is removed. When this is 10 done, the large spring 14 which had been compressed by the drawing down of the mandrel, acting through the cross key 12 and the loose headring 10, will hold the trigger-pin 22 in place. In this setting of 15 the spear, it will be seen that the downward movement of the mandrel carries down the cross-key 17 thereby allowing the loose foot ring 15 to drop down, so that now the gripper-slips 6 are perfectly free to slide on their 20 seats. The socket plugs 25 and 29 are now replaced, and the spear is ready to run in the casing. The slips being free will readily move up to their position of circumferential contraction as the spear runs down the casing, and during this running in, the particular 25 advantage of the loose foot ring 15 appears, in that the spear in running in a hole full of liquid, as is almost always the case, the pressure of the liquid against this loose 30 ring nearly filling the cross sectional area of the casing causes it to rise against the bottoms of the slips and to positively force them up, thereby clearing the casing while the spear is going down the hole. This prevents 35 both the dulling of the slips and injury to the casing. This feature is important, for, in my opinion, many of the failures of spears to take hold of the casing have been caused by the slips becoming dulled by 40 rubbing the casing while going down. When the point is reached for the spear to engage the casing, its descent is stopped and the reverse or lifting movement begins. Immediately 45 the loose foot ring 15 drops back to its cross-key 17, and the slips drop down also, thereby expanding their circumference until they come in contact with the casing. Continued upward movement makes this 50 contact more forceful and they then bite the casing with increasing intensity, as they continue to move down. In this final continued 55 though slight movement, they force down the loose foot ring 15, and this through the cross key 17 forces down the mandrel sufficiently 60 to release the pressure of the mandrel notch 24 on the trigger pin 22, whereupon said pin, under the normal retractive force of its spring 23, will withdraw and thereby trip the mandrel. Thereupon 65 the large spring 14 acting through the head ring 10 and upper cross key 12 will move the mandrel up with relation to the stock sufficiently to permit the reengagement of the safety-latch 26 with the notch 27, and thereafter 70 the spear can not re-set itself while be-

ing pulled out, but must be brought to the surface to be re-set.

The slips being free and capable of independent gripping, each can adjust itself to inequalities in the casing and bite as opportunity affords, which cannot be the case where the slips are operated by a positive connection with the mandrel, for in such case, they must operate in unison. The seating of the mandrel cross keys in the annular recesses in the loose rings is a strong and efficient construction and gives the necessary connection of parts without interfering with their independence. Another advantage, particularly noticeable in connection with 75 the upper ring and upper cross-key is that the recess in said ring forms a cup to confine the key, so that it cannot slip out; nor in case of the key breaking or chipping can the fragments drop down and do damage. 80

I claim:—

1. In a well-casing spear, the combination of a stock having a body portion with upwardly tapered seats, a central bore, and elongated slots traversing said bore above and below the body portion; a mandrel longitudinally slideable in the bore of the stock; an upper and a lower cross-key carried by said mandrel, said keys projecting through and playing in the elongated slots 90 of said stock; a loose head-ring slidably fitted around the stock and arranged to bear up under the upper cross key; a spring around the stock between its body portion and the loose head-ring to hold the ring to the key; a loose foot ring slidably fitted around the stock below its tapered seats and arranged to bear down upon the lower cross key; gripper slips slidably fitted to the tapered seats of the stock above the loose foot-ring; and a trigger carried by the stock, said trigger engaging the mandrel to hold it down when set, and adapted to trip the mandrel to release it when the slips engage the casing in lifting. 100

2. In a well-casing spear, the combination of a stock having a body portion with upwardly tapered seats, a central bore, and elongated slots traversing said bore above and below the body portion; a mandrel longitudinally slideable in the bore of the stock; an upper and a lower cross-key carried by said mandrel, said keys projecting through and playing in the elongated slots of said stock; a loose head-ring slidably fitted around the stock and arranged to bear up under the upper cross key; a spring around the stock between its body portion and the loose head-ring to hold the ring to the key; a loose foot ring slidably fitted around the stock below its tapered seats and arranged to bear down upon the lower cross key; gripper slips slidably fitted to the tapered seats of the stock above the loose foot-ring; a trigger carried by the stock, said trigger engag- 110 115 120 125 130

ing the mandrel to hold it down when set, and adapted to trip the mandrel to release it when the slips engage the casing in lifting, and a safety-latch carried by the stock, said latch engaging the mandrel to lock it against resetting movement when tripped by the trigger.

3. In a well-casing spear, the combination
of a stock having a body portion with tapered
seats, a central bore, and elongated slots
traversing said bore above and below the
body portion; a mandrel longitudinally
slidable in the bore of the stock; a loose
head-ring slidably fitted around the stock
above the body portion, said ring having in
its upper face an annular recess; a loose
foot-ring slidably fitted around the stock
below its body portion, said ring having in
its lower face an annular recess; an upper
cross key fitted in the mandrel, said key
playing in the upper slots of the stock and
lying in the recess of the head-ring; a lower
cross-key fitted in the mandrel, said key
playing in the lower slots of the stock and
lying in the recess of the foot-ring; a spring
around the stock between its body portion
and the loose head ring to hold said ring to
its cross key; gripper slips slidably fitted
to the tapered seats of the stock above the
loose foot-ring; and a trigger carried by the
stock, said trigger engaging the mandrel to
hold it down when set, and adapted to trip
the mandrel to release it when the slips en-
gage the casing in lifting.

35 4. In a well-casing spear, the combination of a stock having a body portion with tapered seats, a central bore, and elongated slots traversing said bore above and below the body portion; a mandrel longitudinally
40 slidable in the bore of the stock; a loose head-ring slidably fitted around the stock above the body portion, said ring having in its upper face an annular recess; a loose foot-ring slidably fitted around the stock
45 below its body portion, said ring having in its lower face an annular recess, an upper cross key fitted in the mandrel, said key playing in the upper slots of the stock and lying in the recess of the head-ring; a lower
50 cross-key fitted in the mandrel, said key playing in the lower slots of the stock and lying in the recess of the foot-ring; a spring around the stock between its body portion and the loose head ring to hold said ring to
55 its cross key; gripper slips slidably fitted to the tapered seats of the stock above the loose foot-ring; a trigger carried by the stock, said trigger engaging the mandrel to hold it down when set, and adapted to trip
60 the mandrel to release it when the slips engage the casing in lifting, and a safety latch carried by the stock, said latch engaging the mandrel to lock it against resetting

65 5. In a well-casing spear, the combination movement when tripped by the trigger.

of a stock having a body portion with upwardly tapered seats, a central bore, and elongated slots traversing said bore above and below the body portion; a mandrel longitudinally slidable in the bore of the stock; 70 an upper and a lower cross-key carried by said mandrel, said keys projecting through and playing in the elongated slots of said stock; a loose head-ring slidably fitted around the stock and arranged to bear up 75 under the upper cross-key; a spring around the stock between its body portion and the loose head-ring to hold the ring to the key; a loose foot-ring slidably fitted around the stock below its tapered seats and arranged 80 to bear down upon the cross-key; gripper slips slidably fitted to the tapered seats of the stock above the loose foot-ring; means adapted to engage the lower end of the mandrel to pull said mandrel down to set it; 85 and a trigger device carried by the stock to hold the mandrel down when set and to trip it when the slips engage the casing in lifting.

6. In a well-casing spear, the combination of a stock having a body portion with upwardly tapered seats, a central bore, and elongated slots traversing said bore above and below the body portion; a mandrel longitudinally slidable in the bore of the stock; an upper and a lower cross-key carried by said mandrel, said keys projecting through and playing in the elongated slots of said stock; a loose head-ring slidably fitted around the stock and arranged to bear up under the upper cross-key; a spring around the stock between its body portion and the loose head-ring to hold the ring to the key; a loose foot-ring slidably fitted around the stock below its tapered seats and arranged to bear down upon the cross-key; gripper slips slidably fitted to the tapered seats of the stock above the loose foot-ring; means adapted to engage the lower end of the mandrel to pull said mandrel down to set it; a trigger device carried by the stock to hold the mandrel down when set and to trip it when the slips engage the casing in lifting, and a safety latch carried by the stock to lock the mandrel against resetting movement when tripped. 110

7. In a well-casing spear, the combination of a stock; gripping devices carried thereby arranged to move into and out of engagement with the casing wall; and a member carried by the stock, adapted upon the running in of the spear, to be actuated by the fluid in the casing to hold the gripping devices out of engagement with the casing wall, and to relieve said gripping devices when the spear is lifted. 120 125

8. In a well-casing spear, the combination of a stock; gripping devices carried thereby arranged to move into and out of engagement with the casing wall; and a ring freely slideable on the stock and adapted

upon the running in of the spear to be forced by the fluid in the casing against the gripping devices to hold them out of engagement with the casing wall, and to relieve 5 said gripping devices when the spear is lifted.

9. In a well-casing spear, the combination of a stock provided with tapered seats; gripper-slips slidably fitted to said seats; and a 10 member carried by the stock below and independent of the gripper-slips and adapted upon the running in of the spear, to be pressed up by the fluid in the casing against the slips to lift and hold them in their contracted position clear of the casing wall, and to drop down to free them when the spear is lifted.
- 15 10. In a well-casing spear, the combina-

tion of a stock provided with tapered seats; gripper-slips slidably fitted to said seats; 20 and a ring slidably fitted on the stock below and independent of the gripper slips, and adapted upon the running in of the spear, to be pressed up by the fluid in the casing against the slips to lift and hold them in 25 their contracted position clear of the casing wall, and to drop down to free them when the spear is lifted.

In testimony whereof I have signed my name to this specification in the presence of 30 two subscribing witnesses.

SMITH VROMAN.
